UNITED STATES PATENT OFFICE.

LEW A. BARNES, OF CHICAGO, ILLINOIS.

APPARATUS FOR BUILDING CONCRETE STRUCTURES.

1,211,812.

Specification of Letters Patent.

Patented Jan. 9, 1917.

Application filed February 1, 1916. Serial No. 75,529.

To all whom it may concern:

Be it known that I, LEW A. BARNES, a citizen of the United States, residing at 5120 Calumet avenue, Chicago, in the county of 5 Cook and State of Illinois, have invented a new and useful Improvement in Apparatus for Building Concrete Structures, of which the following is a specification.

My invention relates, more particularly, 10 to apparatus for forming the beam-portions of structures of concrete, or the like, and supporting the mold-forming elements of such structures; and my objects, generally stated, are to provide novel, simple and improved apparatus for the purpose stated, 15 which may be economically produced, and quickly and readily adjusted to meet the varying conditions presented as to size and shape of structure to be formed.

20 Referring to the accompanying drawings:—Figure 1 is a view in elevation of apparatus constructed in accordance with my invention, the mold-boards being shown in section. Fig. 2 is a plan view of a base- 25 plate or section employed. Fig. 3 is a section taken at the line 3 on Fig. 1 and viewed in the direction of the arrow. Fig. 4 is a broken, enlarged, view in elevation of a portion of the shoring, or support, for the base- 30 plate of the mold, portions thereof being shown in section. Fig. 5 is a similar view of the upper portion of the shoring and a portion of the base-plate; and Fig. 6, a similar view of the lower end of the shoring.

35 As a preface to the following description of my invention, it may be stated that, in practice, the boards, forming the mold-proper, are supported at intervals from supports, or shoring, and as these supports are 40 of the same construction, I have shown only one of them in the drawings.

According to the preferred illustrated embodiment of my invention, the apparatus comprises a standard 7, a cross-member, or 45 base-plate, 8 supported on the upper end of the standard 7, and uprights 9 with brace-members 10 supported on the base-plate and confining the mold-boards, as hereinafter described. The standard 7 is formed of 50 telescoping tubes 11 and 12, the lower, innermost, tube 11 being provided at its lower end with a base 13 at which the standard

rests upon the ground. The outer tube 12 contains at intervals along its length, openings 14 and 15, these openings being disposed at an angle to each other as represented to avoid undue weakening of the structure, though if desired but one series only may be used. The openings 14 and 15 are provided for receiving a pin 16 which extends across the upper end of the tube 11 and serves to support the tube 12, with the parts carried thereby, on the tube 11, the pin being insertible into any of the openings 14 and 15 and this adjustment of the tube 65 serving as a comparatively coarse adjustment of the base-plate 8 in a vertical plane. The upper end of the tube 12 is internally threaded, and screwing therein is the threaded depending section 17 of a plate-member 70 18 which fits flatwise against, and is secured to, the underside of the base-plate 8 the latter, by preference, being formed of structural channel iron, as represented, between the flanges 19 of which the plate-member 18, 75 is located. The threaded connection between the plate-member 18 and the tube 12 affords means for accurately adjusting the base-plate 8 vertically to the desired height.

In the particular illustrated embodiment, 80 the uprights 9 and braces 10 are formed of bars of T-shape in cross-section, the web of the base-plate 8 containing at opposite ends thereof, series 20 and 21 of openings of T-shape and of a size for receiving the uprights 9, these series of openings being so arranged, as shown, as to cause the flat sides of the uprights 9, when inserted therein, to extend transversely of the base-plate 8 and directly oppose each other. The braces 10 85 are preferably provided at their upper ends with bar-sections 22 rigidly secured thereto, and pivoted, as indicated at 23 to the flanges of the adjacent uprights 9.

In practice the base-plate 8 is adjusted to 95 the desired height by first adjusting the tube 12 on the tube 11, as by sliding it thereon, the pin 16 being then inserted into the opening in the tube 12 immediately above the top of the tube 11, and thereupon rotating the tube 12 on the tube 11, as through the medium of a bar (not shown) inserted 100 into one of the openings 14 or 15 in the tube 12, to effect the desired fine adjustment of

the base-plate 8. The boards forming the bottom of the mold are then laid upon the top of the plate 8, these boards, represented at 24, extending across a plurality of the 5 base-plates 8. The boards for forming the side-walls 25 of the mold are preferably assembled with the uprights, on the ground, these boards being nailed, or otherwise fastened, to the uprights 9 to flatwise oppose 10 the flat sides of these uprights. The boards for forming these side-walls, thus assembled with the uprights 9, are then applied to position at the opposite edges of the bottom-wall of the mold, the lower ends of the uprights 15 9 being inserted into the T-openings in the plate 8 immediately beyond the edges of the bottom-wall 24 and the lower ends of the braces 10, which latter are preferably so disposed as to cause the flat sides thereof to 20 be uppermost, inserted into adjacent ones of these openings for interlocking them with the base-plate 8 to brace the uprights 9, as shown in Fig. 2. The openings 20 and 21 are of slightly greater dimensions than the 25 cross-sectional dimensions of the uprights 9, whereby the latter loosely fit these openings, permitting them to be braced in inclined position, if desired, in which case the lower ends of the braces 10 would be adjust- 30 ed farther away from the lower edges of the side-walls 25 and engage those of the openings 20 and 21 adjacent thereto, this adjustment of the uprights 9 being desirable, as, for example, where beams having down- 35 wardly converging side-walls are to be molded.

While I have illustrated and described a particular embodiment of my invention I do not wish to be understood as limiting it 40 thereto, as the same may be modified and altered without departing from the spirit of my invention.

What I claim as new and desire to secure by Letters Patent is:—

45 1. In apparatus of the character set forth, the combination of a plate containing openings in its upper surface, uprights adapted to be inserted into said openings, and braces for said uprights having flanges and adapted to enter others of said openings and bear at said flanges against said plate.

50 2. In apparatus of the character set forth, the combination of a plate containing openings of angular shape in its upper surface, uprights adapted to enter said openings, and braces for said uprights having flanges and adapted to enter others of said openings and bear at said flanges against said plate.

55 60 3. In apparatus of the character set forth, the combination of a plate containing openings of angular shape in its upper surface, uprights of angle-shape in cross-section adapted to enter said openings, and braces 65 for said uprights having flanges and adapt-

ed to enter others of said openings and bear at said flanges against said plate.

4. In apparatus of the character set forth, the combination of a plate containing openings of angular shape in its upper surface, 70 portions of said openings extending lengthwise of said plate and other portions cross-wise thereof, the cross-wise disposed portions of said openings at one end of the plate being disposed at one end of each of the 75 lengthwise-extending portions of said openings, and the cross-wise disposed portions of said openings at the other end of said plate being disposed at the opposite end of the lengthwise-extending portions of said openings, uprights extending into certain of said openings at opposite ends of said plate, and braces for said uprights having flanges and extending into others of said openings in said plate and bearing at said flanges against 80 said plate.

5. In apparatus of the character set forth, the combination of a plate containing openings of angular shape in its upper surface, 85 portions of said openings extending lengthwise of said plate and other portions cross-wise thereof, the cross-wise disposed portions of said openings at one end of the plate being disposed at one end of each of the lengthwise-extending portions of said 90 openings, and the cross-wise disposed portions of said openings at the other end of said plate being disposed at the opposite end of the lengthwise-extending portions of said 95 openings, uprights having flanges extending into certain of said openings at opposite ends of said plate, and braces for said uprights having flanges and extending into others of said openings in said plate and bearing at said flanges against 100 said plate.

6. In apparatus of the character set forth, the combination of a plate containing openings in its upper surface, uprights adapted to be inserted into said openings, and braces 110 for said uprights pivoted thereto and having flanges and adapted to enter other of said openings and bear at said flanges against said plate.

7. In apparatus of the character set forth, the combination of a plate containing openings of angular shape in its upper surface, 115 uprights adapted to enter said openings, and braces for said uprights pivoted thereto and having flanges and adapted to enter other of said openings and bear at said flanges 120 against said plate.

8. In apparatus of the character set forth, the combination of a plate containing openings of angular shape in its upper surface, 125 portions of said openings extending lengthwise of said plate and other portions cross-wise thereof, the cross-wise disposed portions of said openings at one end of the plate being disposed at one end of each of the lengthwise-extending portions of said open- 130

ings, and the cross-wise disposed portions of said openings at the other end of said plate being disposed at the opposite end of the lengthwise-extending portions of said openings, uprights extending into certain of said openings at opposite ends of said plate and braces for said uprights pivoted thereto and

having flanges and extending into others of said openings in said plate and bearing at said flanges against said plate.

LEW A. BARNES.

In presence of—

A. C. FISCHER,
D. C. THORSEN.
